VERTICAL LIFT CONTROL SYSTEM

LeRoy H. Kiesling, Bay Shore, N. Y.

Application December 31, 1947, Serial No. 794,955

17 Claims. (Cl. 187—29)

1

The present invention relates to control circuits and apparatus for conveying systems particularly of the type usually referred to as dumbwaiters, and is particularly concerned with improved automatic control features therefor.

Heretofore, dumbwaiter control systems have included push-button switches and motor relay arrangements with holding circuits or devices, organized in such a way that an operator at one of the dumbwaiter control stations could institute movement of the dumbwaiter car from one station to another by momentarily pressing a control button. The dumbwaiter would respond only if, at the time of the momentary depression, the dumbwaiter car or conveyor was at rest at a station and the door interlock switches all were closed. The motor relay holding circuit would be actuated under these conditions, initiating movement of the dumbwaiter car according to the operator's signal, and the holding circuit would retain the motor in operation until the dumbwaiter car arrived at the station to which it was directed.

Upon arrival of the dumbwaiter car at the destination, a limit switch would be engaged for causing the release of the holding circuit, and the operation of the dumbwaiter drive motor would accordingly be arrested. The dumbwaiter door at that station could then be opened by an operator, and the car could then be unloaded and/or loaded and the door reclosed.

In these former systems, a depression of a control button at a time when a door interlock switch was open, or at a time when the dumbwaiter car was in motion between stations, was entirely without effect. Hence, if an operator at one station depressed a control button to order the dumbwaiter car to that station, but one of the dumbwaiter doors was open at the time of depression of the control button, then the actuation of the control button was entirely ineffective. Persistent depressions of the control button would then be resorted to by the operator, in the hope that the dumbwaiter door eventually would be closed and a subsequent control button depression could constitute its operation. Such dumbwaiter control arrangements suffered by lack of a "memory" feature, all push button depressions prior to readying of the system for the desired trip being in vain. Much time was wasted by employee vigils at dumbwaiter stations, with repeated depressions of the push buttons in effort to obtain an eventual response of the dumbwaiter system.

It is an object of the present invention to provide a dumbwaiter control system wherein a depression of a control button at the time when the dumbwaiter door is open, or at a time when the dumbwaiter car is travelling between stations, will be ineffective to cause an immediate change in the dumbwaiter operation, but will

2

set up such a condition as to cause the desired operation of the dumbwaiter automatically to ensue subsequently, as when the dumbwaiter system is later placed in readiness for the car to make a trip between stations.

In this objective, it is comprehended that a depression of a down control button at a time when the car is travelling upward will automatically result in a subsequent trip downward, and vice versa, and furthermore, it is comprehended that a depression of a control button calling for movement of the car from the station at which it is then located will be given effect immediately upon the closing of a door which had blocked the system operation.

In the achievement of these memory features of automatic delayed operation, the usefulness of the dumbwaiter system would be substantially impaired if the car would be caused to start a return trip immediately after arrival at the station, e. g. as a result of a depression of the up button during a descent of the car. Therefore, arrangements should be included for insuring that after arrival of the dumbwaiter car at a station it will be compelled to remain there a predetermined reasonable time to afford ample opportunity for an operator to open the door for forestalling premature departure of the car and for unloading and/or loading the car.

Accordingly, a further object of the present invention is to provide dumbwaiter control arrangements permitting a dumbwaiter order signal to be given ultimate effect at a subsequent time when the dumbwaiter system is in readiness for a trip, but insuring that the dumbwaiter car will remain at a station an appreciable time before starting on a previously ordered further trip.

Dumbwaiter control arrangements providing these important features are illustrated in the drawings, wherein:

Fig. 1 is a diagram of a control system embodying the present invention applied to a reversible-motor driven dumbwaiter;

Figs. 2 and 3 illustrate modifications applicable to the general system of Fig. 1;

Fig. 4 illustrates a version of the invention applied to a uni-directional motor dumbwaiter;

Fig. 5 shows a uni-directional motor control system incorporating restricted memory features; and

Fig. 6 illustrates a further modification of the invention providing for registration of simultaneous momentary depression of up and down order buttons.

Corresponding reference numerals are applied to common features of the invention carried through the several drawings, for convenience in reference thereto.

Referring now to Fig. 1, a two-stop dumbwaiter

is shown embodying a dumbwaiter car 31 and a reversible motor 10. A first main relay 11 is provided for control of power supplied to the dumbwaiter motor 10 for operation of the car upward and a second relay 13 similar in all respects to relay 11 is provided for control of power supplied to the motor 10 for driving the car downward. Relay 11 comprises a coil 20, a normally closed switch section 22, and three normally open armature switch sections 24, 26 and 28. Relay 13 comprises a coil 30, a normally closed switch section 32, and three normally open switch sections 34, 36 and 38.

A holding relay 15 having a coil 12 and a normally open armature switch 14 is connected for holding a circuit to the coil 20 of relay 11, and a second holding relay 17 having a coil 16 and a normally open armature switch 18 is connected for holding a circuit to the coil 30 of relay 13. A switch 19 is provided for actuating relay 15, and a switch 21 is provided for actuating relay 17. Switches 19 and 21 may comprise "up" and "down" push-button switches for a lower station, and may be duplicated by parallel-connected "up" and "down" switches 23 and 25 at the upper station.

An upper limit switch mechanism 27 is provided with a normally closed switch element arranged to be opened by the dumbwaiter car, as diagrammatically by the top of car 31, upon arrival of the car at the upper station. A lower limit switch 33 is provided to be similarly opened by the arrival of the car 31 at the lower station.

The dumbwaiter car 31 is schematically illustrated as suspended by a cable 41 passing over a sheave 43 and being wound at the end opposite car 31 upon a winch 45 coupled by speed reduction gears 47 to the motor 10. The upper station is shown provided with a door 51 illustrated as slideable to the right for opening, and the lower station is similarly provided with a sliding door 53. Safety interlock switches 55 and 57 are provided at the upper and lower doors respectively, and are arranged to be held closed only when the doors 51 and 53 are entirely closed. The details of the dumbwaiter car, station doors and limit switches, and cable and motor connections are merely schematic illustrations—these details are subject to wide variations in actual installations.

A time delay relay 59 having a coil 59 and a normally closed armature switch 52 is provided for preventing immediate reversal of the direction of operation of the dumbwaiter, to insure that a reasonable opportunity be afforded for access to the dumbwaiter car upon its arrival at a station. This relay 59 is illustrated as provided with a dash-pot time lag arrangement 54, but any other of the well known delay mechanisms may be employed.

The power for the dumbwaiter system is illustrated as brought in through conductor mains 7 and 8. These may be the positive and negative conductors of a direct-current system, or the supply may be an alternating-current supply if desired, single-phase or polyphase with an additional motor supply conductor.

Upper limit switch 27 and switches 23 and 19 in series therewith are connected between main 7 and one terminal of the coil 12 of relay 15, the opposite terminal of this coil being connected to the other main 8. The armature switch 14 of relay 15 is connected in shunt with switches 19 and 23. Conductor 63 between coil 12 and limit switch 27 is also connected to one terminal of relay switch section 32, and through this normally

closed section 32 the circuit is continued to the coil 29 of relay 11.

The connections as thus far described of switch 19 (and parallel-connected switch 23), holding relay 15, limit switch 27 and relays 13 and 11 are so arranged that a momentary depression of an "up" switch when the car is at the upper station is entirely prevented from being effectual. Such a depression of one of the "up" switches when the car 31 is away from the upper station and switch 27 is closed, on the other hand, energizes relay 15 and completes a circuit from conductor 7 through to switch section 32. If relay 13 is not energized, this passes current to the upper terminal of coil 20. In any event, with switch 27 closed, a holding circuit is established through switch 27 and armature switch 14, retaining relay 15 energized; this corresponding to a "self-holding" condition in relay 15 by virtue of its armature switch circuit.

The establishment of this holding circuit condition for relay 15 is independent of the condition of relay 13, but the upper coil terminal of relay 11 can only be brought to the potential of conductor 7 if relay 13 is not energized, with armature switch section 32 accordingly closed.

Sections 24 and 34 of relays 11 and 13 are connected to motor 10 and arranged so that section 24, when closed, produces clockwise rotation of the motor as seen in Fig. 1 and consequent lifting of the car 31, whereas closure of section 34 of relay 13 results in opposite rotation of the motor 10 and downward car movement. Relays 11 and 13 cannot both be energized at any time, because of the cross connections of the circuits of coils 20 and 30 through switch sections 32 and 22.

Down switches 21 and 25, holding relay 17, lower limit switch 33 and coil 30 of relay 13 are interconnected in just the same manner as described above with reference to the corresponding up-control parts, as is plainly shown in Fig. 1.

The lower coil terminals of relays 11 and 13 are connected together by conductor 65, and this conductor is connected through the normally closed armature switch 52 of delay relay 59 and thence through series-connected door interlock switches 57 and 55 to supply conductor 8. Armature switch sections 26 and 36, in parallel, are connected between the lower terminal of coil 59 and supply conductor 7, and the upper coil terminal of relay 59 is connected through the door interlock switches 57 and 55 to supply conductor 8. With these connections, relay 59 will be actuated simultaneously with the actuation of either of relays 11 and 13, the coil 50 remaining energized coextensively with the energization of one of the motor relays, but the armature switch 52 will remain open an appreciable time afterward due to the action of delay mechanism 54. Armature switch sections 28 and 38 of relays 11 and 13 are connected in parallel with armature switch 52, so that the actuation of either of the main relays 11 and 13, though followed immediately by energization of relay 59, will not be interrupted by the opening of switch 52 in series with coils 20 and 30.

The energization circuit for relay 11 is traceable from conductor 7 through an up button switch and thereafter the up holding relay armature switch 14, thence through upper limit switch 27, through switch section 32 of relay 13, through coil 20 of relay 11, thence through switch 52 momentarily and thereafter through section 28 of relay 11, and onward through series-connected door switches 57 and 55 to conductor 8. The en-

ergization circuit for relay 13 is similarly traceable, but through a down-button switch or down holding relay 17 the lower limit switch 33, switch section 22 of relay 11, and alternative paths through switch sections 52 and 38.

The holding relays 15 and 17 are connected in such a way that a holding condition may be established in a selected holding relay by the momentary depression of a button switch for the corresponding direction, provided that the car 31 is not already at the extreme of its travel in that direction. Thus, with the initial conditions as illustrated in Fig. 1, car 31 being at the upper extreme of its travel and holding upper limit switch 27 open, a depression of an up button could not establish a holding condition in relay 15 and it could not energize relay 11, but a depression of a down button produces immediate energization of holding relay 17, at the same time instituting the energization of relay 13. The closure of the armature switch 48 of relay 17 completes a holding circuit to retain its own coil 16 and the coil 30 of relay 13 energized.

The downward shift of the armature of relay 13, through switch section 34, energizes such circuits of motor 10 as to produce counter-clockwise motor shaft rotation, with resultant downward movement of the car 31. At the same time, switch section 32, being opened, safeguards against energization of relay 11; switch section 36, being closed, completes an energization circuit through the coil 50 of relay 59; and switch section 38, being closed, shunts switch section 52 of relay 59 as this section is opened by the energization of coil 50.

If the dumbwaiter doors 51 and 53 remain closed for a sufficient time, the dumbwaiter car 31 will be caused to continue its downward journey until it reaches the lower station, where it opens switch 33 and thus opens the down relay holding circuit, causing the return of relays 17 and 13 to their de-energized conditions, and shutting off the power from motor 10 and the coil 50 of relay 59. As pointed out heretofore, delay mechanism 54 prevents the immediate return of the armature switch 52 to the closed condition, so that even though the armature switch section 32 of relay 13 reclosed immediately upon the arrival of the car 31 at the lower station, the coil circuit of relay 11 cannot immediately be completed for an instantaneous return of the car 31 to the upper station from which it has just descended. At the end of the predetermined delay time of relay 59, however, the armature switch 52 thereof recloses, so that relay 11 may thereafter be energized to send car 31 upward, provided that the dumbwaiter door 53 was left unopened or has been opened and reclosed.

Now, if no up order signal had been given by a momentary depression of one of the up switches 19 and 23 during the downward trip of the dumbwaiter car 31 or during the predetermined delay time assured by relay 59, the car 31 remains inactive even after the delay reclosing of switch section 52 of relay 59. A subsequent depression of an up button sets the system in operation for the trip upward, according to the operating principles outlined above and illustrated in reference to a trip down to the lower station.

As outlined in the introductory paragraphs, however, the present invention goes beyond the modes of operation described above, to provide a delayed response to an order signal instituted by a control button depression, the car and motor system being made to obey the order at a later time when all circuit obstacles are removed from

the coil circuit of the required one of main relays 11, 13. A depression of one of the up buttons 19, 23 during the downward trip previously described, though prevented from causing immediate actuation of relay 11 by the opened-circuit condition of switch section 32, momentarily actuates holding relay 15 and sets up the armature holding circuit thereof, providing a sustained circuit portion from conductor 7 to armature section 32, awaiting the time when relay 13 will have returned to its normal condition with section 32 closed and the armature of relay 59 will have returned to its normal resting position with switch 52 closed. Accordingly, when the predetermined delay interval has elapsed after the arrival of the car 31 at the lower station, the circuit for energization of coil 29 of relay 11 automatically is completed, and the motor 10 then proceeds to haul car 31 upward in obedience to the order instituted by the button depression accomplished during the prior downward trip.

This delayed operation feature, with performance as though the control system were endowed with memory, likewise applies to operation of the system in response to a depression of an order button at a time when one of the dumbwaiter doors 53, 55 was open. In this case, as before, the coil circuits of relays 11 and 13 are prevented from being energized immediately, but the appropriate one of holding relays 15, 17 is actuated to establish a holding circuit from conductor 7 through the coil of the desired one of main relays 11, 13 and through armature switch 52 up to the opened door switch, so that upon re-closure of the dumbwaiter door, the proper main relay is actuated to cause the desired operation of motor 10 and resultant movement of car 31.

For example, considering the dumbwaiter system again in the conditions prevailing in Fig. 1, the door 51 at the upper station may be opened for unloading and/or loading car 31. Meanwhile, an operator at the lower station, requiring the return of the dumbwaiter car, may depress the down button, momentarily closing switch 21 and thereby actuating relay 17. The armature switch thereof, attracted downward, sustains the energization of coil 16, and at the same time retains complete the circuit portion between conductor 7 and the coil 30 of relay 13. This relay 13 remains inactive, however, until an operator at the upper station recloses the door 51, with consequent closure of switch 55 and the resulting completion of the coil circuit of relay 13.

Upon this occurrence, the car 31 is set in motion downward in delayed response to the order signalled by the earlier depression of switch 21, and from this point onward, the operation of the dumbwaiter continues until the car 31 reaches the lower station and the system is automatically turned off, in the same manner as was described above in the case of an immediate response to an order signal given when all circuits were in readiness.

Fig. 2 illustrates an alternative arrangement of the holding relays in such a way that they serve as upper and lower limit switches as well as holding circuit devices. These holding relays, designated 15' and 17', are positioned at the upper and lower stations, respectively, and are provided with respective projecting portions 71 and 73 for engagement by a cam 75 on car 31. The separate limit switches 27 and 33 of Fig. 1 are obviated by this arrangement of the holding relays, since the cam 75 is thus made positively

to insure that a holding relay armature switch, holding closed and retaining the appropriate main relay energized for the approach of the car 31 toward that holding relay, will be opened upon arrival of the car 31 at the destination.

A still further optional form for the holding arrangements is illustrated in Fig. 3. Here, as in Fig. 2, the limit switches 27 and 33 may be dispensed with, the up-movement holding relay 15'' and the down-movement holding relay (not shown) being placed at the upper and lower stations, respectively, and being provided with cam-operated tripping devices as illustrated at 75, 77, 79. Relay 15'' is provided with a mechanical latch 79 on the armature, arranged to rest normally below a receiving projection on the pivoted arm 77.

Upon actuation of the coil 12 of the holding relay 15'', the armature thereof is drawn upward, so that the armature switch 14 is closed. At the same time, the latch 79 is brought into engagement with the receiving projection on arm 77, which rests on pin 81 and sustains the armature in the attracted position so that it does not return to the normal position after the momentary actuation of the coil circuit. Thus, the relay is mechanically held in the closed-circuit condition, as illustrated in Fig. 3—A, while the car 31 is hauled upward in response thereto.

As the car 31 arrives at the upper station, the cam 75 engages the end of the pivoted arm 77, swinging this arm over to the left and disengaging the latch 79, so that the armature switch system falls open. The motor circuit is consequently de-energized, and the dumbwaiter propulsion system is thus brought to rest in generally the same manner as described in reference to Fig. 1.

The choice of the details of a holding arrangement among those illustrated in Figs. 1, 2 and 3 will depend upon the details of a particular dumbwaiter system.

Fig. 4 illustrates the application of the control circuits of Fig. 1 to a dumbwaiter system of the endless chain or belt type employing a non-reversing motor drive. The cable 41 by which the dumbwaiter car 31 is suspended is attached at its upper end to a pin 101 fastened to a link of an endless chain 103. This chain passes over an upper sprocket 105 and a lower sprocket 107, the sprockets being spaced apart by a vertical separation of the order of the distance of travel required of the dumbwaiter car between upper and lower stations.

One of the sprockets, e. g. sprocket 105, is coupled as through a speed-reduction gear system 109 to a drive motor 110. This motor is connected in series with shunt-connected armature sections 24 and 34 of relays 11 and 13, between the mains 7 and 8. Hence, the motor 110 drives the chain 103 in only one direction (illustrated as the counter-clockwise direction) whether activated through relay 11 or through relay 13. As is readily apparent, however, such uni-directional operation provides alternate upward and downward trips of the dumbwaiter car 31.

The upper and lower limit switches are arranged for operation by a cam 111 affixed to the chain 103, such switches being illustrated at 27' and 33'. The push-button switches 19, 21, 23 and 25, relays 15, 17 and 59, and door switches 55 and 57 are connected with relays 11 and 13 in the same manner as in Fig. 1, and these parts of the system of Fig. 4 operate in just the same

manner as in Fig. 1. The system is illustrated in Fig. 4 as being in operation with the dumbwaiter car rising, approaching the upper station. Relay 15, having been momentarily actuated through one of the up button switches 19, 23, has established a holding circuit retaining the upper terminal of the coil 20 of relay 11 in circuit with conductor 7, and relay 11 is energized, providing the rotation of motor 110 for drawing the car 31 upward.

When the car 31 reaches the upper station, the cam 111 will lift the contact bar of upper switch 27', breaking the holding circuit of relay 15 and accordingly restoring relays 15 and 11 to their normal rest conditions. This will open the supply circuit of motor 110, so that the drive chain 103 is brought to rest.

The delayed operation or memory features of Fig. 1 are fully provided in the system in Fig. 4. If, for example, a down order is registered by a momentary depression of one of the down push-button switches as the car 31 is being lifted toward the upper station, e. g. at the moment of the conditions illustrated in Fig. 4, such a depression institutes a holding circuit in relay 17. Such a circuit does not cause the car 31 to be carried on through the upper station end of its route and again immediately downward, but instead, provides for completion of the coil energization circuit of relay 13 only after the predetermined delay interval insured by relay 59. Furthermore, a signal given at a time when a door switch is open is given delayed effect, exactly as with the system of Fig. 1.

Fig. 5 illustrates a version of the present invention capable of providing delayed operation in response to a push-button order signalled while the car 31 is at rest at a station, its immediate response being then prevented either by an open door switch or by an open condition of the switch 52 of delay relay 59 during the predetermined period following arrival of the car 31 at the station. This system, employing a smaller number of control elements with somewhat simplified circuit connections, lacks the feature of delayed operation in response to a push-button order signalled while the system is in motion with the car 31 travelling from one station to the other.

Only one push-button switch is provided at each station, the lower station switch being shown at 119 and the upper station switch being shown at 123. A single holding relay 115 is provided, and a single main control relay 121 is likewise employed. The door switches 55 and 57, the endless chain 103 on sprockets 105 and 107, and the uni-directional drive motor 110 coupled through speed reduction gears 109 are arranged in generally the same manner as shown in Fig. 4. In the system of Fig. 5, two cams 111' and 111'' are provided on the chain 103, and a single station-stop switch 127 is arranged to be actuated by whichever of these two chain cams next arrives in contact therewith.

The control elements in Fig. 5 all are illustrated as at rest, the car 31 being at the lower station, the doors (which, though not shown, may be considered as slidable to the left to be opened) being closed, the relays 59, 115 and 121 being in their normal conditions, and the lower-stop cam 111'' being in the position just beyond switch 127 to which it is carried by the drive system momentum, so that switch 127 is closed.

Now, a depression of one of the push-button switches 119, 123 will momentarily energize the holding relay 115, and through the armature

switch 114 thereof the holding circuit is thereafter sustained. Through armature switch 114, the energization circuit through coil 120 of main relay 121 is established, the coil current momentarily flowing through the armature switch 52 of relay 59. This energization of coil 120 pulls the armature of relay 121 downward, closing switch section 134 and energizing the motor 110 therethrough, and producing clockwise rotation of chain 103 so that the car 31, after moving downward slightly, is drawn upward toward the upper station. With the energization of coil 120, switch sections 136 and 138 of relay 121 are closed also, the former completing the circuit for energization of the delay relay 59, and the latter at the same time shunting the armature switch 52 of the delay relay, preventing the circuit to coil 120 from being opened.

The holding circuit of relay 115 now remains complete, with continued operation of the system, until the car 31 has been drawn up to the height of the upper station, the cable coupling pin 101 having been drawn to the top of sprocket 105. At this point, cam 111 depresses stop switch 127, momentarily opening the holding circuit of relay 115, and through relay 121, arresting the energization of motor 110. Here, again, the cam 111 is carried just beyond switch 127 by the momentum of the drive system, so that switch 127 is reclosed in readiness for a further trip of the car. The connections of switches 119 and 123 with relay 115 and relay 121 are such that even if the lowermost one of the cams failed to be carried beyond switch 127, and remained in the position holding this switch open, the motor 110 is actuated through relay 121 during the depression of one of the push-button switches, so that the offending cam is carried on beyond switch 127 and the holding circuit is then established for insuring the proper completion of the dumbwaiter car trip, to be terminated in the usual manner by the further operation of switch 127.

The time delay relay 59 operates here in just the same manner as in Figs. 1 and 4, forestalling the further energization of the main relay 121 until the predetermined time interval has elapsed after the last preceding trip. A depression of one of the push-button switches while the holding circuit through relay 115 is complete and the car 31 is in motion has no effect, since these switches are shunted at such times by armature switch 114. A depression of one of the push-button switches while the car 31 is at rest at one of the stations is fully effective, however, in the same manner as with the systems of Figs. 1 and 4. An open door switch at the moment of depression of the push-button switch, or an open condition of armature switch 52 following a very recent trip of the car 31, can prevent immediate operation of relay 121 and motor 110, but a holding circuit is established through relay 115, awaiting the readiness of the circuit through armature switch 52 and door switches 57 and 55 for delayed operation of the system.

The embodiments of the present invention as thus far described have in common the requirement that an order for a return to a station cannot be effectually signalled to the dumbwaiter system until initiation of the movement of the car away from that station. As heretofore pointed out with respect to Fig. 1, for example, a holding circuit condition for returning the car to a station could only be set up after the institution of progress of the car from that station. If the up button was depressed when the car was at rest

at the upper station, for example, such a depression would be entirely ineffectual. Only a depression of the up button continuing until after the commencement of the downward movement, or a depression of the up button initiated after that time, could establish the holding circuit condition required to insure the subsequent automatic return of the car to the upper station.

An embodiment of the invention providing for the establishment of a holding condition for returning the car to a station, in response to a signal given even before its departure from that station, in addition to all other features of the system of Fig. 1, is illustrated in Fig. 6. Up and down holding relays 215 and 217, respectively are provided for actuation through an associated one of control button switches 19, 21, 23, 25, through one of the limit switches 27, 33, generally in the same manner as described in connection with Fig. 1. Similarly, a pair of main relays 211 and 213 are provided for actuation of the up and down propulsion windings of the dumbwaiter drive motor, and are connected to the time delay relay 59 as in Fig. 1, for insuring that the car will wait at a station for at least a predetermined interval to enable an operator at that station to gain access to the car and to hold it as long as necessary for unloading and/or loading it.

Two further relays 201 and 203 are provided in Fig. 6, connected generally intermediate between the holding relays and the main motor control relays; and car cam-operated switches 207 and 209 are added in circuit with the coils of these further relays.

Relay 215 comprises coil 212 and three normally open armature switch sections 214, 204 and 206. Relay 217 comprises coil 216 and three normally open armature switch sections 218, 205, and 208. Relay 201 comprises a coil 243, two normally closed switch sections 241 and 242, and a normally open armature switch section 240. Relay 203 similarly comprises a coil 247, two normally closed armature switch sections 245 and 246, and a normally open switch section 244. Relay 211 comprises a coil 220 and three normally open armature switch sections 224, 226 and 228. Similarly, relay 213 comprises a coil 230 and three normally open armature switch sections 234, 236 and 238.

Switch sections 246 and 242 are connected in series with coils 220 and 230, respectively, so that operation of relay 211 is blocked when relay 203 is actuated, and operation of relay 213 is blocked when relay 201 is actuated. Switch section 241 is connected in series with coil 247, and switch section 245 is connected in series with coil 243, so that when one of the intermediate relays 201, 203 is energized, it blocks the energization of the other.

Sections 240 and 244 are connected in parallel with limit switches 27 and 33, respectively. Switch section 204 is connected in series with switch section 246 and coil 20 of relay 211, so that closure of this section at a time when relay 203 is not energized causes the actuation of relay 211 and the consequent upward movement of the dumbwaiter car. Similarly, switch section 205 is connected in series with switch section 242 and the coil 230 of relay 213.

With the circuit connections as illustrated in Fig. 6, a car return holding circuit condition can be established when the car is at rest at a station. For example, if the car is at rest at the upper station, an up button can be depressed for 75 the storage of a signal to be given effect after the

car has moved down to the lower station and waited there the predetermined delay interval. When the car is at rest at the upper station, the car cam 75 holds switch 207 closed and upper limit switch 27 open. Through switch 207 and switch section 241, the coil 247 of relay 203 is energized, so that the actuation circuit of relay 211 is blocked and switch section 244 is closed across the upper limit switch 27.

If an up button were depressed under the conditions illustrated, it would momentarily effect the actuation of the coil of holding relay 215 whereupon armature switch section 214 would retain this circuit complete, the relay being thus arranged for self-holding. No current would immediately be permitted to flow through either of switch sections 204, 206, however, since sections 245 and 246 of relay 203 are held open so long as relay 203 remains energized, and relays 203 and 201 are so interconnected with car operated switches 27, 33, 207 and 209 that relay 203 must remain energized until the car has moved to the lower station.

A depression of a down button, on the other hand, not only would result in the establishment of a down order circuit condition in self-holding relay 217 but also would result in the down-direction operation of the car drive motor as a result of the actuation of relay 213 through switch sections 205 and 242. As the car consequently proceeds downward, the descending cam 75 first allows the upper limit switch 27 to be reclosed, and soon thereafter clears switch 207 so that the latter is opened. Neither the closing of switch 27 nor the opening of switch 207 has any immediate effect upon the operation of the dumb-waiter system, as closed switch section 244 shunts switch 27 and closed switch section 208 of the actuated holding relay 211 shunts switch 207.

As the car approaches the lower station, cam 75 first closes switch 209, thereby providing such a condition that relay 201 will be actuated if the energization of relay 203 is momentarily interrupted. Then, as the car reaches the position desired at the lower station, cam 75 opens the lower limit switch 33, opening the circuit through coil 248 of relay 217 and thereby bringing its self-holding circuit condition to an end. The resultant interruption of current flow through switch section 208 causes the release of the armature of relay 203, and relay 201 is thereupon energized through switch 209 and the now reclosed armature switch section 245. Furthermore, the opening of switch section 205 of holding relay 217 at the holding condition interruption breaks the circuit to motor relay 213, arresting the energization of the motor and stopping the descent of the car at this position at the lower station.

As in Fig. 1, relay 59 is energized coextensively with either motor control relay, and at the time of de-energization of relays 213 and 59, the armature switch 52 of relay 59 remains open the predetermined delay interval to block an immediate return of the car to the upper station whence it has just descended.

If there has been no depression of an up button since the last preceding trip of the car up to the upper station, the holding relays are now both left in non-energized condition, and the system is capable of receiving and holding a down order, or capable of receiving an up order and responding thereto after the predetermined interval required for the reclosing of the time delay relay 59 in the same manner as discussed with reference to Fig. 1.

Let it be supposed that an up button was depressed before commencement of the car's descent, as either before the depression of the down button or simultaneously therewith, or that it was depressed during the downward movement of the car. Regardless of the sequence of the depressions of the up and down buttons while the car was away from the lower station, the appropriate holding circuit condition was established 5 in the up holding circuit in addition to the above discussed down holding circuit, and moreover, the interconnections of relays 201 and 203 with relay 203 energized insured that the car would be moved downward before it could respond to the up order.

It will be apparent from the above outline of the operation of the arrangement of Fig. 6 that the one of the intermediate relays 201 and 203 which is energized blocks the operation of the 20 motor relay connected therethrough and therefore prevents operation of the motor in one direction; and it will similarly be apparent that a change-over occurs between relays 201 and 203 upon each arrival of the car at one of the terminal stations, and only then. Moreover, these 25 added relays, together with the associated switches 207 and 209, provide all the features of the system of Fig. 1 with the added feature that a return trip holding circuit condition can be 30 established even before the commencement of a trip of the car from a station.

Since many changes could be made in the above construction and many apparently widely different embodiments of this invention could be 35 made without departing from the scope thereof, it is intended that all matter contained in the above description or shown in the accompanying drawings shall be interpreted as illustrative and not in a limiting sense.

40 I claim:

1. A dumbwaiter system comprising a dumb-waiter car, means for guiding said car between predetermined stations, means for propelling said car between said stations, control means including an electric actuation circuit for controlling said propelling means, manually operable controller means to be actuated for signalling an order for the car to proceed to a station, means actuatable by said manually operable controller for holding a connection to said electric actuation circuit, means for tripping said holding means upon arrival of said car at the station to which ordered, and means for blocking the energization of said actuation circuit but leaving intact said connection held by said holding means; said propelling means comprising an electric motor, said control means comprising an up control relay and a down control relay including armature switch elements connected to said motor, said manually operable controller means comprising an up button switch and a down button switch for selective directional control of said dumbwaiter car, and said holding means comprising a first holding relay and a second holding relay, said first relay being coupled to said up button switch to be initially energized therethrough and having an armature switch coupled to the actuation circuit of said up control relay, and said second holding relay 60 being coupled to said down button switch to be initially energized therethrough and having an armature switch coupled to the actuation circuit of said down control relay, said holding means further comprising means for retaining one of 65 said armature switches set from the time of actu-

13

ation of the respective push button switch until tripped by said tripping means.

2. A dumbwaiter system as defined in claim 1, wherein each one of said holding relays comprises an armature switch section connected to the actuation circuit thereof to supply actuation-sustaining energy thereto after a momentary energization through the related button switch.

3. A dumbwaiter system as defined in claim 2, wherein said tripping means comprises means operated upon arrival of said car at a station for interrupting the actuation-sustaining energy flow through said armature switch section.

4. A dumbwaiter system as defined in claim 3, wherein said tripping means comprises means for blocking the circuit through the up button switch when the car is at the uppermost station and for blocking the circuit through the down button switch when the car is at the lowermost station.

5. A dumbwaiter system comprising a dumbwaiter car, means for guiding said car between predetermined stations, means for propelling said car between said stations, control means including an electric actuation circuit for controlling said propelling means, manually operable controller means to be actuated for signalling an order for the car to proceed to a station, means actuatable by said manually operable controller for holding a connection to said electric actuation circuit, means for tripping said holding means upon arrival of said car at the station to which ordered, and means for blocking the energization of said actuation circuit but leaving intact said connection held by said holding means; said blocking means comprising at least one station door interlock switch for blocking the actuation of said control means so long as a station door is open.

6. A dumbwaiter system as defined in claim 5, said actuation circuit comprising an electromagnetic control unit coupled to said propelling means for energizing it to propel said car to one of said stations, said means actuatable by said manually operable controller means comprising a relay having an armature contactor connected to its coil to sustain energization after initiation thereof through said manually operable controller means, and said means for tripping said holding means comprising a normally closed cam-operated switch arranged to be opened by arrival of said car at said one station.

7. A dumbwaiter system comprising a dumbwaiter car, means for guiding said car between predetermined stations, means for propelling said car between said stations, control means including an electric actuation circuit for controlling said propelling means, manually operable controller means to be actuated for signalling an order for the car to proceed to a station, means actuatable by said manually operable controller for holding a connection to said electric actuation circuit, means for tripping said holding means upon arrival of said car at the station to which ordered, and means for blocking the energization of said actuation circuit but leaving intact said connection held by said holding means; said blocking means comprising a time delay relay having a control circuit connected to said control means to be actuated substantially coextensively therewith and to block the actuation of said control means a predetermined time interval after each tripping of said holding means and consequent termination of actuation of said control means.

8. A vertical lift control system comprising a car, means for guiding said car between an upper station and a lower station, means for propelling

14

said car between said stations, first and second main control relays connected to said propelling means for upward propulsion and downward propulsion, respectively, first self-holding relay means connected to said first main control relay for sustaining actuating current therethrough and second self-holding relay means connected to said second main control relay for sustaining actuating current therethrough, upper station interrupter means for interrupting the holding of said first self-holding relay means when said car reaches said upper station, lower station interrupter means for interrupting the holding of said second self-holding relay means when said car reaches said lower station, and means connected in circuit with said first and second main control relays for blocking the actuation therethrough of said propelling means until predetermined conditions prevail in the dumbwaiter system, said first and second self-holding relay means being independent of said means for blocking actuation whereby a holding condition can be commenced in one of said self-holding means or continued therein if previously commenced notwithstanding actuation of said propelling means being blocked by said actuation blocking means.

9. A system as defined in claim 8, wherein said upper station interrupter means comprises means for preventing the establishment of a self-holding condition in said first self-holding relay means when said car is at said upper station and said lower station interrupter means comprises means for preventing the establishment of a self-holding condition in said second self-holding relay means when said car is at said lower station, whereby said upper and lower station interrupter means safeguard against operation of said propelling means to send said car beyond the normal range of movement between said stations.

10. A system as defined in claim 9, wherein each of said self-holding relay means comprises a relay having an actuation coil circuit and a normally open armature switch connected thereto for sustaining actuating current thereto following a momentary attraction of the armature, and the one of said station interrupter means associated therewith comprises a normally closed limit switch connected in series with said normally open armature switch and means for opening said limit switch upon arrival of said car at a station.

11. A system as defined in claim 8, wherein each of said self-holding relay means comprises a relay having an actuation coil circuit and a normally open armature switch connected between said actuation coil circuit and the power connections therefor to sustain an actuated condition therein after momentary actuation of the self-holding relay, and the interrupter means comprises means coupled to said car for forcing said self-holding relay open.

12. A system as defined in claim 8, wherein said first self-holding relay means is capable of receiving and holding a call to said upper station when said car is at rest at said upper station and said second self-holding relay means is capable of receiving and holding a call to said lower station when said car is at rest at said lower station, whereby a signal condition may be instituted at a station when the car is at that station to insure its return thereto after any departure thereof.

13. A system as defined in claim 8, wherein said first self-holding relay means comprises means for receiving and holding a call to said upper station at any time irrespective of position or motion 75 of said car, and said second self-holding relay

15

means comprises means for receiving and holding a call to said lower station at any time irrespective of position or motion of said car.

14. A system as defined in claim 8, wherein said first self-holding relay means comprises means for receiving and holding a call to said upper station when said car is in downward movement or at the lower station, and said second self-holding relay means comprises means for receiving and holding a call to said lower station when said car is ascending or at said upper station, said first self-holding relay means being prevented from receiving a call when said car is at rest at said upper station and said second self-holding relay means being prevented from receiving a call when said car is at rest at said lower station.

15. A vertical lift system comprising a car, means for propelling said car along a substantially vertical path between an upper station and a lower station, an up order switch button, a down order switch button, means responsive to an actuation of said up order switch button when said car is at rest at either station or in downward transit for holding an up order circuit condition, means responsive to an actuation of said down order switch button when said car is at rest at either station or in upward transit for holding a down order circuit condition, means for actuating said propelling means in response to said up order circuit condition, means for actuating said propelling means in the direction to provide downward progress of said car in response to said down order condition, means for blocking the upward propulsion of said car in response to said up order circuit condition until said car has remained at said lower station a predetermined period of time following its arrival there, means for blocking the downward propulsion of said car until said car has remained at said upper station a predetermined period of time following its arrival there, means for interrupting said up order circuit condition upon arrival of said car at said upper station in response thereto, and means for interrupting said down order circuit condition upon arrival of said car at said lower station in response thereto, each of said holding means being capable of responding to the respective switch button actuation irrespective whether an order circuit condition is held in the other holding means.

16. A conveying system comprising a car, a hatchway containing said car and having two stations between which said car can be propelled in said hatchway, first electrically operable means for propelling said car toward a first one of said two stations, second electrically operable means for propelling said car toward the second one of said two stations, a first self-holding circuit for receiving and holding a call and for actuating said first electrically operable means, a second self-holding relay circuit for receiving and holding a call and for actuating said second electrically operable means, said first and second electrically operable means being interconnected for each when energized to block the actuation circuit of the other, said first self-holding relay circuit including a normally open relay armature contactor and a first car-operated station-stop switch connected in series in its actuation circuit, the switch being normally closed but being arranged to be opened by arrival of the car at said first station, said second self-holding relay circuit including a normally open relay armature contactor and a second cam-operated station-stop switch connected in series in its actuation circuit, the switch being normally closed but being arranged to be opened

65

70

16

by arrival of the car at said second station, at least one manually operable momentary contact switch in shunt with each of said armature contactors for holding circuit initiation when the car is absent from the station for which the call is initiated, first means coupling said first self-holding relay circuit to said first electrically operable means, and second means coupling said second self-holding relay circuit to said electrically operable means, said first and second coupling means including the interconnections therebetween.

17. A control system comprising a car, a hatchway containing said car and having two stations between which said car can be propelled in said hatchway, first electrically operable means for propelling said car toward a first one of said stations, second electrically operable means for propelling said car toward the second one of said two stations, a first self-holding relay for receiving and holding a call for said car to be propelled to said first station, a second self-holding relay for receiving and holding a call for said car to be propelled to said second station, a first intermediate relay connection between said first self-holding relay and said first electrically operable means, a second intermediate relay connected between said second self-holding relay and said second electrically operable means, said first and second intermediate relays being interconnected for prevention of concurrent actuations thereof, a first normally closed switch and a first normally open switch arranged for cam operation upon arrival of said car at said first station, a second normally open switch and a second normally closed switch for cam operation upon arrival of said car at said second station, at least one first-station call switch and a normally open armature contactor of said first self-holding relay connected in parallel with each other and in series with said first normally closed switch in the actuation circuit of said first self-holding relay, at least one second-station call switch and a normally open armature contactor of said second self-holding relay connected in parallel with each other and in series with said second normally closed switch in the actuation circuit of said second self-holding relay, said first self-holding relay having a normally open contactor connected in shunt with said second normally open switch and in series with the actuation circuit of said second intermediate relay including the cross-connection through a normally closed contactor of said first intermediate relay, and said second self-holding relay having a normally open contactor connected in shunt with said first normally open switch and in series with the actuation circuit of said first intermediate relay including the cross-connection through a normally closed contactor of said second intermediate relay, said first and second intermediate relays each being connected to block the energization of the respective ones of said first and second electrically operable means when energized.
